UNITED STATES PATENT OFFICE

2,462,311

COLLAR AND TIE HOLDER

Richard C. Erdmann, Minneapolis, Minn.

Application March 18, 1947, Serial No. 735,464

3 Claims. (Cl. 2—132)

1

This invention relates to new and useful improvements and structural refinements in so-called collar holders, and the principal object of the invention is to provide a device of the character herein described which is adapted to retain in a neatly adjusted position both, the wings of the collar as well as the tie.

A further object of the invention is to provide a collar and tie holder which will accommodate collar wings of various sizes and shapes, and which will effectively support the tie in a somewhat forwardly projected, neatly arranged position.

Another object of the invention is to provide a collar and tie holder which is simple in construction and which may be quickly and easily installed or removed.

An additional object of the invention is to provide a collar and tie holder which, once adjusted, will be properly retained in position, so that further adjustment thereof while in use is unnecessary.

A still further object of the invention is to provide a collar and tie holder which will readily lend itself to economical manufacture.

Another object, in fact, one of the more important objects of the invention is to provide a collar and tie holder, the presence of which cannot be readily detected, since it is fully hidden by both, the collar wings and the tie.

With the above more important objects in view and such other objects as may become apparent as this specification proceeds, the invention consists essentially of the construction and arrangement of parts as shown in the accompanying drawings in which:

Figure 1 is a front elevational view of the invention;

Figure 2 is a side elevational view thereof;

Figure 3 is a front elevational view, showing the invention (in phantom lines) in situ on a collar and tie;

Figure 4 is a front elevational view of a modified embodiment of the invention;

Figure 5 is a fragmentary front elevational view of another modified embodiment thereof, and

Figure 6 is a fragmentary front elevational view of a still further modified embodiment of the same.

Like characters of reference are used to designate like parts in the specification and throughout the several views.

Referring now to the accompanying drawings in detail, and more specifically, to Figures 1, 2 and 3, the invention consists of a collar and tie holder designated generally by the reference character 10, the same embodying in its construction a length of wire-like rod 11 angulated substantially as shown so as to provide a horizontally disposed mid-portion 12 and a pair of downwardly extending end portions 13.

2

The portions of the rod 11 between the portions 12 and 13 form what may be referred to as outwardly and upwardly extending guides 14, the latter being of an inverted U-shaped configuration, as will be clearly apparent from the accompanying drawing.

In effect, the entire rod 11 may be regarded as having an inverted U-shaped configuration, this being further emphasized by the provision of a pair of tubular extension sleeves 15, each of which is secured in any suitable manner to one of the rod portions 13.

The connection of the rod portions 13 to the sleeves 15 is indicated at 16, each of the sleeves accommodating a slidably cup 17. Each of the sleeves also accommodates a suitable compression spring 18 which is seated in the cup for the purpose of urging the latter toward the free extremity of the sleeve, in other words, in the direction of the arrow 19 in Figure 1.

Each of the cups 17 is provided with a pin 20 which extends outwardly from the sleeve and terminates in a pointed extremity 21. These pointed extremities of the two pins are adapted to engage the wings 22 of the collar 23, while the guides 14 are receivable within the closed, channel-like upper edge 23 of the collar, as is best shown in Figure 3.

It will be apparent that the springs 18 will urge the points 21 into engagement with the wings 22 of the collar and also, by virtue of said springs, the invention will readily accommodate collar wings of various sizes and types.

The essence of novelty of the invention resides in the provision of a downwardly and forwardly extending tongue 24 which simply consists of a U-shaped wire rod, the end portions of which provide convenient loops or eyes 25, so that the tongue is pivotally, or at least movably or swingably attached to the mid-portion 12 of the rod 11.

It will be noted that the closed end of the tongue 24 is arcuated as indicated at 26 and that it is provided with a pair of spaced, forwardly and upwardly extending teeth 27.

The tongue 24 is normally urged forwardly by resilient means, the same consisting of a pair of rod-like members 28, each of the latter being wound around or otherwise secured to one side member of the tongue 24, substantially as shown at 29.

It will be noted that the members 28 are also wound around the mid-portion 12 as indicated at 30, and the free extremities of the members are suitably secured to the end portions 13 of the rod 11, as at 31. Matters are so arranged that the members 28 normally urge the tongue 24 in the direction of the arrow 32, substantially as already explained.

When the invention is placed in use, the extremities 21 are engaged with the collar wings

22 as already described, and the teeth 27 of the tongue 24 are similarly engaged with the underside of the tie 33, preferably, of the tie knot 34. At the same time, the closed end portion 26 of the tongue 24 will also engage the tie knot, and it will be found that in this manner, the tie, as well as the collar wings, will be effectively retained in a neatly arranged position.

Suitable stops may be provided on the pins 28 adjacent the points 21, whereby the points are prevented from penetrating too far in the material of the collar.

Referring now to the modified embodiment of the invention illustrated in the accompanying Figure 4, the same has been designated generally by the reference character 40 and is substantially similar to the embodiment already described.

However, the holder 40 consists of a simple, U-shaped rod member 41 provided with the guides 42 and terminating at the extremities thereof in the collar engaging points 43. It will be noted that in this embodiment of the invention, the spring-pressed cups 17 have been eliminated, and furthermore, the member 41 is formed integrally with the tongue 44.

In other words, the mid-portion 45 of the member 41 is angulated to provide the tongue 44, the latter being equipped with a pair of teeth 46, similar to the aforementioned teeth 27.

However, in order to prevent the side members 47 of the member 41 from spreading, a suitable wire loop 48 is employed, as will be clearly apparent from the accompanying drawing. The rod 41 is angulated to provide a pair of relatively opposed detents or seats 49 at the upper end of the tongue 44, the seats 49 being adapted to receive the loop 48, substantially as shown.

With reference to the further modified embodiment of the invention illustrated in the accompanying Figure 5, the holder indicated generally at 50 is substantially similar to the holder 40 insofar as the U-shaped member 51 is concerned.

However, the tongue 52 is of a substantially V-shaped configuration and the end portions thereof are wound around the mid-portion 53 of the member 51 as indicated at 54, whereupon said end portions are secured to the side members 55 of the member 51, as at 56.

The tongue 52 is, in this instance, provided with only one tooth, namely, the tooth 57, as will be clearly apparent.

Finally, with reference to the still further modified embodiment of the invention indicated by the general reference character 60 in the accompanying Figure 6, the same consists of a U-shaped rod member 61 similar to the aforementioned members 51 and 41, but the tongue 62 provided in this instance is of an inverted, T-shaped configuration, as will be clearly understood.

The transversely extending portion of the tongue terminates in a pair of spaced, upwardly and forwardly directed teeth 63, while the stem, or the upper end of the tongue is movably secured to the mid-portion of the member 61, as indicated at 64.

The tongue is normally urged forwardly by means of a pair of resilient members 65 which are substantially similar to the aforementioned members 28.

The use of the holders 40, 50 and 60 is sub-

stantially the same as that of the holder 10, the primary difference between the various holders being in their respective structures, as described.

Thus, it will be noted that the holders 10 and 60 embody the particular resilient means 28 and 65 respectively for urging the tongue toward the tie, while the resilient means employed in the holder 50 are formed integrally with the tongue itself. On the other hand, the member 41 in the holder 40 is considered to possess sufficient inherent resiliency so as to urge the tongue 44 forwardly, thereby effectively eliminating the resilient means employed in the other embodiment of the invention.

Finally, it should be understood that if desired, the spring-pressed cups 17 and the sleeves 15 may, of course, be employed in association with the holders 40, 50 and 60, as well as with the holder 10, as described.

It is believed that the advantages and use of the invention will be clearly understood from the foregoing disclosure, and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A collar and tie holder, comprising in combination, a substantially U-shaped member terminating in pointed extremities adapted to engage the collar wings, a movable, downwardly extending tongue provided at the mid-portion of said member, a plurality of upwardly projecting teeth disposed adjacent the lower extremity of said tongue, and resilient means for projecting said tongue in a forward direction, said teeth being engageable with the tie.

2. A collar and tie holder comprising in combination, an inverted U-shaped member including a mid-portion and a pair of downwardly extending arms, said arms terminating in pointed extremities engageable with collar wings, a downwardly extending and forwardly projectable tongue movably attached at the upper end thereof to the mid-portion of said member, resilient means on said mid-portion for urging said tongue forwardly, and an upwardly and forwardly directed tooth at the lower end of said tongue, said tooth being engageable with a tie knot.

3. The device as defined in claim 2 wherein said means comprises a pair of resilient rod-like extensions on said tongue, said extensions being wound around the mid-portion of said member and anchored to said arms.
